UNITED STATES PATENT OFFICE.

HARRY A. FREDERICKS, OF PORT ANGELES, WASHINGTON.

DONKEY-ENGINE CRANE.

1,380,292.

Specification of Letters Patent.

Patented May 31, 1921.

Application filed February 10, 1920. Serial No. 357,497.

To all whom it may concern:

Be it known that I, HARRY A. FREDERICKS, a citizen of the United States of America, residing at Port Angeles, in the county of 5 Clallam and State of Washington, have invented new and useful Improvements in Donkey-Engine Cranes, of which the following is a specification.

The object of the invention is to provide 10 a means for use in connection with donkey engines and like structures whereby the raising and removal of the drums, which are usually of great weight for the purpose of giving access to the bearings thereof for 15 relining, babbitting and the like, may be facilitated, to avoid the inconvenience ordinarily encountered in connection with this operation due to the necessity of jacking or prying up the drums or of manually lifting the same, as well as the loss of time incident to an operation which frequently should be completed within a brief interval 20 in order to avoid interference with the functions of the apparatus, and to this end the 25 invention consists in a crane or transporting frame embodying hoisting means and embodying a construction and combination of parts of which a preferred form is illustrated in the accompanying drawings, 30 wherein:

Figure 1 is a side view.

Fig. 2 is a plan view.

Fig. 3 is an end elevation partly in section.

Fig. 4 is a transverse section of the track rails.

Fig. 5 is a detail view of a portion of one of the track rails.

Fig. 6 is a similar view of one of the 40 socket plates by which the inner ends of the track rails are supported and secured against longitudinal displacement.

The apparatus is designed especially for 45 use in connection with donkey engines of the type employed as hoisting means in connection with building operations and having the furnace 10, bed plate 11, bearing pedestals 12 and drums 13 of which the latter are usually of metal and of a weight 50 which renders the displacement thereof for the purpose of repairing or relining the bearings a matter of difficulty involving a considerable expenditure of time and effort

and usually necessitating the discontinuance for a considerable period of time of the use 55 of the engine.

The crane embodying the invention consists essentially of parallel track rails 14 supported by standards 15 and 16 provided at their upper extremities with seats 17 for 60 the reception of the bars forming the rails to the end that when not in use the frame may be folded or the parts disconnected for arrangement within a small space for storage; said rails being traversed by travelers 65 or carriers 18 from which depend hoisting devices 19.

Obviously the crane may be set up in position to span the drums of the donkey engine wherever the latter may be employed, 70 and to this end the standards are provided at their lower ends with spurs indicated at 20 for effective engagement with the supporting surface, and laterally inclined braces 21 may be used in connection with 75 the terminal standards 16 to give transverse rigidity while connecting the track rails at suitable points are transverse brace bars 22 having terminal clips 23 for engagement with said rails. Also as a means of increasing 80 the rigidity of the structure the inner ends of the track rails may be provided with depending studs 24 for engagement with sockets 25 carried by plates 26 which may be riveted or otherwise permanently secured to 85 the wall of the furnace casing 10.

In the construction illustrated the travelers or carriers consist of rollers 27 from the pintles of which depend yokes 28 which extend under the rails and serve as means 90 of attachment for the eyes or hooks 29 on the upper pulley blocks of the hoisting devices. The lower pulley blocks indicated at 31 carry stirrups or hooks 32 for engagement with the drums or drum spindles, and obviously 95 when it is desired to displace a drum to give access to its bearings, the frame having been erected as indicated, the stirrups 32 of the opposite hoisting devices carried respectively by the travelers or carriers may 100 be engaged with the drum and when the latter has been raised to a sufficient elevation the drum may be moved longitudinally of the frame and deposited upon a suitable rest or vehicle which may be arranged in the 105 space beyond the base 11 and between the

same and the terminal standards 16, or may be held in the elevated position until the bearings have been repaired.

In the peripheries of the rollers 27 there are provided sockets 33 at intervals for engagement by a lever or pin 34 indicated in Figs. 1 and 2 to serve as a means of moving the travelers or carriers along the track, and said pins or levers are also adapted to perform the additional function, in the event that the track rails should not be exactly horizontal, of serving as stops or chocks to bear at their outer ends upon the track rails to hold the carriers or travelers at any given place upon the rails, to prevent the movement of the same beyond the point desired.

From the above description it will be seen that the apparatus may be conveniently set up over the engine whenever required without involving any considerable loss of time and without during the period of erection serving to interfere with the operation of the engine, and when desired a drum may be removed with but slight loss of time to permit of the operator giving the proper attention to the bearings and then replaced without necessitating any extended period of idleness of the engine and without imposing any objectionable effort upon the operator.

What is claimed is:

1. An apparatus for the purpose described having parallel track rails and means for supporting the same, carriers or travelers mounted upon said rails and consisting of rollers having depending stirrups, and hoist-

ing devices suspended from the stirrups and provided with means for engaging engine drums, said rollers being provided with peripheral sockets for engagement by an operating pin or rod.

2. A drum removing crane for donkey engines comprising in combination with the engine furnace, sockets mounted on said furnace wall, track rails provided with depending terminal studs engageable in said sockets, standards supporting said track rails at points remote from said sockets and having means at their upper ends for detachable engagement with said track rails, transverse bracing means detachably engaged with and spanning said rails, and carriers mounted upon the rails and provided with drum hoisting means.

3. An apparatus for the purpose indicated having parallel track rails and means for supporting the same, carriers or travelers mounted upon said rails and consisting of rollers provided with depending stirrups, hoisting means suspended from the stirrups and provided with engine drum engaging elements, the said rollers being provided with radially disposed uniformly spaced peripheral sockets, and operating pins removably engaged in said sockets for imparting angular movement to the rollers as well as acting as chocks for the same by engagement with said rails as herein shown and specified.

In testimony whereof I affix my signature.

HARRY A. FREDERICKS.
